CLAIM

The ornamental design for an jackfruit knife, as shown and described.

DESCRIPTION

FIG. 1 shows a perspective view of the jackfruit knife showing my new design.

FIG. 2 is a left side view of the jackfruit knife, the right side a mirror image of the left side.

FIG. 3 is a top view of the jackfruit knife.

FIG. 4 is a front view of the jackfruit knife.

FIG. 5 is a bottom view of the jackfruit knife.

FIG. 6 is a rear view of the jackfruit knife.

FIG. 7 is a perspective view of the jackfruit knife attached to a handle; and,

FIG. 8 is a side view of the jackfruit knife attached to an oscillating tool.

The broken lines shown in the drawings are for illustrative purposes only and form no part of the claimed design.

1 Claim, 3 Drawing Sheets
